UNITED STATES PATENT OFFICE

149,906

DESIGN FOR A CANOPY FOR USE WITH
CHILDREN'S FURNITURE

Alfred E. Puls, Cleveland, Ohio, assignor to Metropolis Bending Company, Metropolis, Ill., a corporation of Illinois

Application April 15, 1946, Serial No. 128,618

Term of patent 14 years

(Cl. D34—5)

To all whom it may concern:

Be it known that I, Alfred E. Puls, a citizen of the United States, residing at Cleveland, in the county of Cuyahoga and State of Ohio, have invented a new, original, and ornamental Design for a Canopy for use with Children's Furniture, of which the following is a specification, reference being had to the accompanying drawing, forming part thereof, wherein Fig. 1 is a perspective view and Fig. 2 a plan view of a canopy for use with children's furniture embodying my new design. The dominant features of the design reside in the portions illustrated in full lines.

I claim:

The ornamental design for a canopy for use with children's furniture, as shown and described.

ALFRED E. PULS.
